UNITED STATES PATENT OFFICE.

THOMAS PATRICK CUMMINGS, OF CHICAGO, ILLINOIS.

PLUMBING DEVICE.

Application filed October 22, 1927. Serial No. 228,094.

My invention relates to plumbing devices and more particularly to a novel plug adapted to be used in testing pipes, drains, and similar plumbing structures.

5 The object of my invention is to provide a plug of the kind described that will be of simple and inexpensive construction, light in weight, and efficient for the purpose intended.

10 Other objects and advantages of the method and construction herein employed will appear more fully in the hereinafter specification when taken in connection with the accompanying drawings, in which:

15 Figure 1 is an elevational view, partly in section of my device.

Figure 2 is an elevational sectional view of my device in operative position within a pipe, showing a head of water sealed thereby.

20 Figure 3 is a plan view of my novel plug. With more particular reference to the drawings herein, similar characters of reference indicating corresponding parts in the several views, 11 designates a hollow, annular, rubber member having an air valve 12 to admit and expel air from the interior of the plug. 13 is a spool having a passageway 14 to admit the bolt 15 having an integral disc head 16 and threads 17 to accommodate the nut 18,—the bolt also having a square end 19 with a view to holding the shaft of the bolt in fixed position while the nut is being adjusted. 20 is a disc having a hole 21 through which the stem of the air valve 12 is passed.

25 Upon referring to Figure 2 the mode of operation of my device will be understood in connection with the following brief description:

30 In the plumbing art it is frequently necessary to test and repair water pipes, drains, and similar plumbing adjuncts, with the water removed therefrom. After the repairs have been made, to test a pipe, such as A, shown in Figure 2, it will merely be necessary to insert one of my novel plugs, of an appropriate size, with the annular member partly inflated. By attaching the valve 12 to an air pump of conventional pattern, air may now be introduced into the hollow annular member 11 until the pressure is sufficient to protrude and impinge the periphery thereof against the sides of the pipe A, thereby sealing the pipe water tight. The pipe may now be filled with water with a view to

determining whether the repairs made are adequate. Hitherto, when making repairs, 55 it has been necessary for the plumber or his assistant to carry a metal plug, the average weight of which was seven or eight pounds, making it a laborious task to carry around when the usual rounds of repair assignments 60 were made. The plug comprising my invention weighs about a pound, and is particularly adapted to effect a water-tight seal.

It is to be understood that the form of my invention herewith shown and described is 65 susceptible of some change and modification; hence, I do not wish to limit myself to the precise details of construction as set forth, but desire to avail myself of such variations and modifications as fairly fall within the 70 scope of the appended claims.

What I claim as new and desire to secure by Letters Patent is:

1. A plug of the kind described, comprising an annular inflatable member; a spool 75 within said annular member, a pair of discs adapted to cooperate with said spool and inflatable member, means to clamp said discs to said spool, said means comprising a threaded member having a shank provided with a 80 square end in order to prevent rotation of the threaded member when adjustments thereto are desired, and means whereby said inflatable member may be expanded.

2. A plug of the kind described, comprising an annular inflatable member; a pair of discs adapted to impinge against said inflatable member, clamping means engaging said discs, and additional means integral with 85 said clamping means to prevent rotation thereof when adjustments are desired, and means whereby said inflatable member may be expanded to press against the interior walls of a water pipe.

3. A plug of the kind described, comprising a spool within an annular inflatable member, a plurality of members, means whereby said plurality of members are adapted to contact with said spool in restraining the periphery of said inflatable member to expand 100 against the interior walls of a pipe, and additional means integral with said first mentioned means to prevent rotation thereof when adjustments are desired, whereby a plug is formed, adapted to seal said pipe.

4. A plug of the kind described, comprising

ing an annular inflatable member, a spool axially apertured, located in the center of said inflatable member, a plurality of discs having central perforations registering with said apertured spool, a threaded bolt passing through said discs and spool, and means on the end of said bolt to prevent rotation there-

of when adjustments are required to the said plug, and pneumatic means whereby said plug may be expanded to seal a water pipe, ¹⁰ in a leak proof manner.

In testimony whereof I have signed my name to this specification.

THOMAS PATRICK CUMMINGS.
